C. C. BLAKE.

WELT GUIDE.

APPLICATION FILED NOV. 24, 1915. RENEWED JUNE 2, 1921.

1,403,227.

Patented Jan. 10, 1922.

UNITED STATES PATENT OFFICE.

CHARLES C. BLAKE, OF BROOKLINE, MASSACHUSETTS, ASSIGNOR TO C. C. BLAKE,
INCORPORATED, OF BOSTON, MASSACHUSETTS, A CORPORATION OF NEW YORK.

WELT GUIDE.

1,403,227.

Specification of Letters Patent. Patented Jan. 10, 1922.

Original application filed August 16, 1913, Serial No. 785,142. Divided and this application filed November 24, 1915, Serial No. 63,327. Renewed June 2, 1921. Serial No. 474,524.

To all whom it may concern:

Be it known that I, CHARLES C. BLAKE, a citizen of the United States, residing at Brookline, in the county of Norfolk and State of Massachusetts, have invented a new and useful Improvement in Welt Guides, of which the following is a specification.

The present invention relates to welt guides which are used in the manufacture of shoes to guide and support the welt during the inseam sewing operation.

In the welt shoe devised by me the welt is slit longitudinally along one edge face in order to form a base in the interior of the welt to hold the inseam stitches.

The object of the present invention is to produce a welt guide which will properly hold the welt hereinbefore referred to during the inseam sewing or fastening operation.

To the accomplishment of this object the features of the present invention consist in certain devices, combinations and arrangements of parts fully set forth hereinafter, the advantages of which will be readily understood by those skilled in the art.

The various features of the present invention will be readily understood from an inspection of the accompanying drawings illustrating the best form of the invention at present known to the inventor, in which,

Figure 1 is a side elevation of the welt guide and associated parts, and

Fig. 2 is a front elevation of the welt guide.

The machine illustrated in the drawings comprises a straight eye-pointed needle 1, an awl 2, a gage 3, a pair of gages or feet 4, a looper 5 and a knife or gouge 6. The parts above briefly referred to are constructed and arranged in the same manner and operated by the same mechanism as the corresponding parts of the machine disclosed in application for Letters Patent of the United States filed by me August 16, 1913, Serial No. 785,142, of which the present application is a division.

The welt 7 to be sewn to the lasted shoe is provided with a longitudinal slit 8 along one edge face, which forms an upper flap 9 and a lower flap 10 in the body portion of the welt. In order to guide this welt properly for the operation of the sewing instrumentalities the machine is provided with a

welt guide 11 embodying the features of the present invention. The welt guide 11 is provided with a V-shaped nose 12 which engages the base of the slit 8 and the interior faces of the upper and lower flaps. The welt guide 11 is provided with a foot 13 which engages the outside face of the upper flap 9. A second foot 14 on the welt guide engages the outside face of the lower flap 10. The foot 14 is also provided with a face 15 which extends beyond the flap and engages the body portion of the welt to support it and prevent its buckling. The foot 13 is bifurcated (Fig. 2) to permit the material of the welt to hump beneath the foot during the passage of the tools through the work. The needle and awl operate through an opening 16, formed in the welt guide, which is arranged substantially in the vertical plane of the feet 13 and 14 (Fig. 2).

The welt guide 11 depends from a slide 17 which is arranged to slide beneath a cover plate 18 upon the top of a slide 19 for the awl 2. The welt guide is held in position against the welt by a spring 20 one end of which is secured to a pin 21 on the awl and needle carrier and the other end of which is secured to a pin 22 on the slide 17. With this construction the welt slit longitudinally along one edge is held properly in position for the operation of the sewing tools.

It will be apparent to those skilled in this art, and with the general objects of the present invention in view, that changes may be made in the details of structure, the described and illustrated embodiment thereof being intended as an exploitation of its underlying essentials the features whereof will be definitely stated in their true scope in the claims hereto appended.

What is claimed as new, is:—

1. A guide for guiding a welt slit longitudinally along one edge consisting of a nose arranged to engage the base of the slit and both of the interior faces of the flaps, all parts of the guide being out of contact with the unslit edge of the welt, substantially as described.

2. A guide for guiding a welt slit longitudinally along one edge consisting of a nose arranged to engage the base of the slit and both of the interior faces of the flaps, and a foot arranged to engage the outside face of the upper flap, all parts of the guide being

- out of contact with the unslit edge of the welt, substantially as described.
3. A guide for guiding a welt slit longitudinally along one edge consisting of a nose arranged to engage the base of the slit and both of the interior faces of the flaps, and a foot arranged to engage the outside face of the bottom flap, all parts of the guide being out of contact with the unslit edge of the welt, substantially as described.
4. A guide for guiding a welt slit longitudinally along one edge consisting of a nose arranged to engage the base of the slit and both of the interior faces of the flaps, and a foot arranged to engage the outside face of the bottom flap, said foot having an additional face arranged to engage the body portion of the welt, all parts of the guide being out of contact with the unslit edge of the welt, substantially as described.
5. A guide for guiding a welt slit longitudinally along one edge consisting of a nose arranged to engage the base of the slit and both of the interior faces of the flaps, and a pair of feet arranged to engage the top and bottom faces of the upper and lower flaps, respectively, substantially as described.
6. A guide for guiding a welt slit longitudinally along one edge consisting of a nose arranged to engage the base of the slit and both of the interior faces of the flaps, and a bifurcated foot arranged to engage the outside face of the upper flap, substantially as described.
7. A guide for guiding a welt slit longitudinally along one edge consisting of a nose, arranged to engage in the slit, having an opening therein for the passage of a tool therethrough, substantially as described.
8. A guide for guiding a welt slit longitudinally along one edge consisting of a nose, arranged to engage in the slit, having an opening therein for the passage of a tool therethrough; and a foot arranged to en-

gage the outside face of the upper flap in substantially the vertical plane of the opening, substantially as described.

9. A guide for guiding a welt slit longitudinally along one edge consisting of a nose, arranged to engage in the slit, having an opening therein for the passage of a tool therethrough; and a foot arranged to engage the outside face of the lower flap in substantially the vertical plane of the opening, substantially as described.

10. A guide for guiding a welt slit longitudinally along one edge consisting of a nose, arranged to engage in the slit, having an opening therein for the passage of a tool therethrough; and a pair of feet arranged to engage the top and bottom faces of the upper and lower flaps, respectively, in substantially the vertical plane of the opening, substantially as described.

11. A welt guide comprising a passage for the welt, and a separate passage for a tool through the guide opening into the first passage and arranged in a plane intersecting the guided welt intermediate the top and bottom faces thereof.

12. A guide for guiding a welt slit longitudinally along one edge comprising a nose arranged to engage the base of the slit provided with a passage for a tool therethrough.

13. A guide for guiding a welt slit longitudinally along one edge consisting of a nose arranged to engage in the slit in the welt and co-operating guiding surfaces to engage the flaps of the slit in the welt, said guide leaving the unslit edge of the welt free.

14. A guide for guiding a welt slit longitudinally along one edge consisting of co-operating guiding surfaces constructed to engage the internal and external faces of the slit in the welt, and arranged out of contact with the unslit edge of the welt.

CHARLES C. BLAKE.
